CLAIM

The ornamental design for a cornhole board, as shown and described.

DESCRIPTION

FIG. 1 is a front, left and top perspective view of a cornhole board showing my new design;

FIG. 2 is a front, right and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a perspective view thereof, shown in a folded configuration; and,

FIG. 10 is an enlarged view thereof; taken from the encircled portion 10 in FIG. 1.

The dash-dash broken lines in the drawings depict portions of the cornhole board and form no part of the claimed design.

The dash-dot-dash broken lines in the drawings are included to indicate a partially enlarged view and form no part of the claimed design.
